CLAIM

The ornamental design for a platelet-rich plasma activation device as shown and described.

DESCRIPTION

FIG. 1 is a perspective view of a platelet-rich plasma activation device showing our new design;

FIG. 2 is a front side elevational view of the platelet-rich plasma activation device of FIG. 1;

FIG. 3 is a rear side elevational view of the platelet-rich plasma activation device of FIG. 1;

FIG. 4 is a right side elevational view of the platelet-rich plasma activation device of FIG. 1;

FIG. 5 is a left side elevational view of the platelet-rich plasma activation device of FIG. 1;

FIG. 6 is a top plan view of the platelet-rich plasma activation device of FIG. 1; and,

FIG. 7 is a bottom plan view of the platelet-rich plasma activation device of FIG. 1.

The dashed broken lines shown in the drawings depict portions of the platelet-rich plasma activation device that form no part of the claimed design. The dash-dot-dash broken lines shown in the drawings define the bounds of the claimed design and form no part of the claimed design.

1 Claim, 7 Drawing Sheets
